The ornamental design for a charging stanchion, as shown and described.

DESCRIPTION

FIG. 1 is a front, top, right perspective view of a charging stanchion according to a first embodiment of our new design;

FIG. 2 is rear, top, left perspective view of the charging stanchion shown in FIG. 1;

FIG. 3 is a top plan view of the charging stanchion shown in FIG. 1;

FIG. 4 is a bottom plan view of the charging stanchion shown in FIG. 1;

FIG. 5 is a front elevational view of the charging stanchion shown in FIG. 1;

FIG. 6 is a right side elevational view of the charging stanchion shown in FIG. 1;

FIG. 7 is a rear elevational view of the charging stanchion shown in FIG. 1;

FIG. 8 is a left side elevational view of the charging stanchion shown in FIG. 1;

FIG. 9 is a front, top, right perspective view of a charging stanchion according to a second embodiment of our new design;

FIG. 10 is rear, top, left perspective view of the charging stanchion shown in FIG. 9;

FIG. 11 is a top plan view of the charging stanchion shown in FIG. 9;

FIG. 12 is a bottom plan view of the charging stanchion shown in FIG. 9;

FIG. 13 is a front elevational view of the charging stanchion shown in FIG. 9;

FIG. 14 is a right side elevational view of the charging stanchion shown in FIG. 9;

FIG. 15 is a rear elevational view of the charging stanchion shown in FIG. 9;

FIG. 16 is a left side elevational view of the charging stanchion shown in FIG. 9;

FIG. 17 is a front, top, right perspective view of a charging stanchion according to a third embodiment of our new design;

FIG. 18 is rear, top, left perspective view of the charging stanchion shown in FIG. 17;

FIG. 19 is a top plan view of the charging stanchion shown in FIG. 17;

FIG. 20 is a bottom plan view of the charging stanchion shown in FIG. 17;

FIG. 21 is a front elevational view of the charging stanchion shown in FIG. 17;

FIG. 22 is a right side elevational view of the charging stanchion shown in FIG. 17;

FIG. 23 is a rear elevational view of the charging stanchion shown in FIG. 17; and,

FIG. 24 is a left side elevational view of the charging stanchion shown in FIG. 17.

The broken lines in the drawings depict portions of the charging stanchion that form no part of the claimed design.
